GEOEGE WESTINGHOUSE, OF PITTSBURGH, PENNSYLVANIA.

BLADES.

1,061,648.

Specification of Letters Patent.

Patented May 13, 1913.

Application filed August 27, 1910. Serial No. 579,247.

To all whom it may concern:

Be it known that I, GEORGE WESTINGHOUSE, a citizen of the United States, and a resident of Pittsburgh, in the county of Allegheny and State of Pennsylvania, have made a new and useful Invention in Blades and Means for Mounting Blades, of which the following is a specification.

My invention relates to blading and particularly to turbine blading.

An object of my invention is to produce a new and improved blading and also new and improved means for assembling and mounting blades.

These and other objects I attain by means of the blades and blading illustrated in the drawings accompanying this application and forming a part thereof.

In the drawings, Figure 1 is a perspective view of blading embodying my invention shown in connection with a portion of a blade mounting element. Figs. 2 and 3 are perspective views of blades embodying my invention. Fig. 4 is a transverse section of a group of blades taken along the longitudinal axes of the blades and illustrates a modification of my invention.

For convenience of description, I have illustrated my invention in connection with blades adapted to be employed in a turbine, in which motive fluid is delivered to a row of blades, and after having traversed the blades is re-directed and re-delivered to the blades. I do not desire to limit the application of my invention to blades for this type of turbine, nor to the arrangement or construction illustrated, and I desire it to be understood that the drawings are merely illustrative and that various changes and modifications may be made without departing from the spirit and scope of my invention.

Referring to the drawings,—each blade illustrated consists of a body portion 4, a mounting portion 5 and a shrouding flange 6. The body portion is substantially crescent shaped in cross section, being provided on one side with a concave working face 7 and on the other side with a convex working face 8. The convex face is divided into two portions by an intermediate spacing piece 9, which is formed integrally with the body portion of the blade and which is provided with a convex face 10 adapted to engage the concave face of the next adjacent blade when the blades are assembled in a row. The

shrouding flange 6 provided at the end of each blade projects laterally beyond the convex face of the blade in the same direction as the spacing piece 9 and is provided with a convex edge adapted to engage the concave face of the next adjacent blade and to co-operate with the flanges 6 of all the other blades to form a shroud for the row of blades when the blades are assembled in a row.

I contemplate assembling the blades into short segments prior to mounting them on the blade carrying element, and to this end I provide holes 11, which extend transversely through the body portion of the blades and the intermediate spacing pieces 9. I then assemble several blades on a binding member or pin 12, which is arc shaped and extends through the holes 11 in the blades. The pins 12 fit snugly into the holes 11 and are so arranged that the separate segments may be assembled on the blade mounting element into an organized row, in which the pins 12 all co-operate to hold the blades in place and to laterally strengthen the row of blades. I accomplish this by so arranging the pins 12 that they project beyond the last blade of each short segment at one end of the segment and do not extend entirely through the final blade at the other end of the segment. With this arrangement the projecting end of the pin of one segment extends into the hole 11 of the adjacent blade of the next segment when the segments are assembled in an annular row.

The mounting portion 5 of each blade is formed integrally with the body portion; in fact, each blade may be milled out of a single piece of metal, the flange 6, the intermediate spacing piece 9 and the base portion 5 being formed by the milling operation. The mounting portion consists of a shoulder 13 and a narrow tongue 14 which projects coaxially with the body portion of the blade. The shoulder 13 is so constructed that it co-operates with the concave face of the next adjacent blade and forms a spacing piece between the mounting ends of the blades. The tongue 14 is adapted to fit snugly into a slot 15 formed in a mounting element 16, and each blade is rigidly and positively secured in place on the mounting element by means of rivets 17, which extend through transversely extending holes 18 provided in the tongue 14 of each blade and registering holes 19 provided in the blade mounting element 16. The over-hanging portions of the base

portion 5 located on each side of the tongue 14 of each blade are adapted to contact with the peripheral faces of the element 16 and to some extent add to the lateral stiffness of 5 the blade when it is mounted in place on the blade mounting element.

The holes 18 and 19 in the blades and the mounting element respectively may be drilled prior to locating the blades in the 10 slot of the mounting element; or the blades may be first located in place on the mounting element and the holes 18 and 19 drilled in the same operation.

It will be apparent that the blades are 15 spaced at each end and at an intermediate point between their ends when they are in place on the blade mounting element and that the flanges 6, the intermediate spacing pieces 9 and the base portions 5 coöperate 20 with the concave faces of the adjacent blades to secure the blades of a row against lateral motion. In addition to this, the pins 12 firmly unite the blades of each segment and the separate segments together in a rigid 25 organized structure and add to the lateral stiffness of the blades. The intermediate spacing piece 9, in addition to spacing the blades, divide the passages between the blades into two sets of working passages 30 through which the fluid flows in opposite directions in the blades illustrated in the drawings. The flanges 6, spacing pieces 9 and the shoulder 13 of the blades are preferably so formed that the blades occupy 35 radial positions when assembled in segments.

In Fig. 4, I have illustrated blades in which the shrouding flanges 6 are provided with holes 21 through which a binding member or pin 22 extends. The construction of 40 the blades shown in Fig. 4 is similar to that of the blades shown in Figs. 1, 2 and 3.

It will be apparent that the outer ends of the blades may be flanged and secured together without the necessity of providing 45 the intermediate spacing pieces 9, and without the necessity of providing intermediate binding member or pin 12. It will also be apparent that I may employ two or more binding members 22 at the outer ends of 50 the blades, or that I may employ two or more pins 12 extending through the intermediate portions of the blades. With some constructions I may find it preferable to provide two binding members 22 in place of the 55 single member illustrated, since the flanges

6 could be thinner and since the same strength of binding member could be obtained.

Having thus described my invention, what I claim is:

1. A blade segment comprising a plurality of blades provided with intermediate spacing pieces located between the ends of the blades and formed integrally therewith and a binding member extending through 65 the blades and spacing pieces.

2. A blade segment comprising a plurality of blades, means formed integrally with the blades for dividing the passages between the blades into two sets of working passages 70 and a binding member passing through said means for securing the blades together.

3. A blade segment comprising a plurality of blades, means for dividing the passages between the blades into two sets of 75 working passages and a binding member extending through the blades and said means.

4. In combination with a blade mounting element, a plurality of blades provided with mounting portions, and shrouding flanges 80 located at opposite ends of the blades and means extending through the blades and located between said flanges and said mounting portions for securing them together.

5. In combination with a blade mounting 85 element, a plurality of blades provided with integrally formed spacing pieces located at their outer or free ends, and intermediate spacing pieces located between the outer ends and the mounting ends of the blades, means 90 for securing said blades to said mounting element and a binding member extending through said spacing pieces for securing the blades together.

6. In combination with a blade mounting 95 element, a plurality of blades, a binding member extending through the outer or free ends of the blades, means for securing said blades to said mounting element and a binding member extending through the blades 100 and located between said mounting means and said first mentioned binding member.

In testimony whereof, I have hereunto subscribed my name this 23rd day of August, 1910.

GEO. WESTINGHOUSE.
